(57) **CLAIM**

The ornamental design for a recessed lighting fixture, as shown and described

DESCRIPTION

FIG. 1 is a perspective view of a recessed lighting fixture showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front view shown in use embedded in a ceiling; and,

FIG. 9 is a cross-sectional view taken along line 9—9 in FIG. 5 with the internal parts omitted.

The broken lines in the drawings depict unclaimed environmental subject matter.
